(57) **CLAIM**

The ornamental design for a plush rabbit, as shown and described.

DESCRIPTION

FIG. 1 is a front elevation view of a plush rabbit showing our new design;

FIG. 2 is a left side elevation view thereof;

FIG. 3 is a rear elevation view thereof;

FIG. 4 is a right side elevation view thereof;

FIG. 5 is a top plan view thereof; and,

FIG. 6 is a bottom plan view thereof.

The broken lines shown in the drawing are for illustrative purposes only and form no part of the claimed design.

The nose of the plush rabbit shown in the drawing is lined for the color red.
